UNITED STATES PATENT OFFICE.

BENJAMIN W. TUCKER, OF SOUTH ORANGE, NEW JERSEY, ASSIGNOR TO CORONA TYPEWRITER COMPANY, INC., A CORPORATION OF NEW YORK.

TYPE-WRITING MACHINE.

1,279,045.

Specification of Letters Patent. Patented Sept. 17, 1918.

Application filed May 1, 1916. Serial No. 94,660.

To all whom it may concern:

Be it known that I, BENJAMIN W. TUCKER, a citizen of the United States, and a resident of South Orange, county of Essex, and State 5 of New Jersey, have invented certain new and useful Improvements in Type-Writing Machines, of which the following is a full, clear, and exact description.

This invention relates more particularly 10 to a front strike or other visible typewriting machine, in which the main frame has relatively movable parts to adapt the machine to be collapsed when not in use.

One of the principal objects of the invention 15 is to provide a simple and efficient writing machine wherein the platen carriage and its associated parts may be mounted upon one main frame part and the type action upon another main frame part, and the said 20 parts relatively movable in a vertical direction only, whereby the machine may be collapsed to materially reduce its height and move the parts from a normal operative position to a more compact and inoperative 25 one.

Another object of the invention is to provide 30 a frame construction for a collapsible typewriting machine wherein the mechanisms are so mounted that either a type segment shift or a platen case shift may be employed.

Other objects of the invention are to provide 35 simple means whereby the platen carriage and its associated parts including the universal bar may be all mounted upon a vertically movable frame part and in a vertical plane only to adapt the platen carriage to be located at the rear of the type bars and the ribbon mechanism located directly above 40 and at one side of the type-bars when the parts are in a compact position ready for transportation purposes; to provide simple means whereby the frame parts may be positively held in a normal operative position 45 or in a compact position; and to provide simple means for mounting a universal bar in position to be engaged by the type-bars during the printing movement thereof, and the said universal bar adapted to operate 50 escapement mechanism and ribbon mechanism.

A further object of the invention is to provide 55 a writing machine of a visible type wherein the platen carriage and the associated parts including the universal bar has

a complete break connection with the type action and spacing mechanism in the normal operative and inoperative positions, and which platen carriage and the associated parts, including the universal bar are adapted to be moved to an inoperative compact position relative to the type action. 60

A still further object of the invention is to provide a machine which is simple in construction and may be readily made and assembled. 65

With these and other objects in view, the invention will be hereinafter more particularly described with reference to the accompanying drawings, which form a part of 70 this application, and will then be pointed out in the claims at the end of the description.

In the drawings, Figure 1 is a plan view, partly broken away, of one form of machine 75 embodying the invention, showing the parts in a normal operative position.

Fig. 2 is a longitudinal section from front to rear of the machine, taken on the line II—II of Fig. 1. 80

Fig. 3 is a side elevation of the machine, showing the parts in a collapsed condition.

Fig. 4 is a vertical section showing the mounting for the ribbon spools and for the relatively movable parts of the machine 85 frame, the section being taken on the line IV—IV of Fig. 5.

Fig. 5 is a fragmentary side elevation of the parts shown in Fig. 4.

Fig. 6 is a section similar to Fig. 4, except 90 that the ribbon spools have been moved to a compact position.

Fig. 7 is a fragmentary perspective view, showing the construction and mounting for the universal bar. 95

Fig. 8 is a vertical longitudinal section, partly in elevation, showing a case shift mechanism adapted to shift the platen instead of the type basket, as shown in the other figures. 100

Fig. 9 is a plan view of one side of the machine with the carriage removed, showing the construction of the frame and mechanism whereby the platen carriage and the supporting frame part therefor may be raised 105 or lowered or shifted; and

Fig. 10 is a longitudinal sectional view showing the type action and parts of the machine of Figs. 8 and 9, a part of the machine being shown in side elevation. 110

In Figs. 1 to 7 the main frame 10 comprises a base member or frame part 11, and a vertically movable frame part 12 on which part a carriage 13 is mounted to travel transversely thereof. Rotatably held in the carriage is the usual platen 14. The base or main frame part 11 comprises sides or plates 15 which at their forward portions may be connected by a substantially L-shaped transversely extending bar 16, either separate therefrom or formed integral therewith as a single casting, as preferred, and on the said base member or part 11 are the usual rubber feet 17. A transversely extending bar 18 is held between the sides 15 of the base frame part 11, and held to said transversely extending bar are pivot rods 19. The transversely extending bar 18 is slotted transversely along the upper and lower edges thereof, and pivotally held on the rods 19 and within the slots of said bar 18 are levers 20 and 21. The levers 20 and 21 are arranged in pairs, and each pair of said levers at the forward ends are pivotally held to a part 22 of a key-lever 23. The key-levers 23 are arranged in banks or groups and form a standard or universal keyboard, and have the upper portions of one bank extending in an opposite direction to those of another bank. As shown there are three banks of key-levers each having a key 24. The intermediate key-levers are substantially vertical, while the upper portions of the levers of one of the banks extend upwardly and forwardly, and the upper portions of the other bank of key-levers extend upwardly and rearwardly, and by reason of their arrangement and connection with the levers 20 and 21 a substantially uniform touch is provided. The keys of the different banks are arranged at relatively different heights for ready operation, as is usual in typewriting machines, and each key-lever is adapted to be restored and held in its normal position by means of a spring 25 one end of which is held to the transversely extending bar 16 and the other end to an arm of the lower lever 21. The levers 20 and 21 are connected in pairs at their inner ends by links 26, and these links are each connected by a rod or link 27 to an arm 28 of a type-bar 29. The type-bars 29 are pivoted at their inner ends to a pivot rod 30, which is held to a type segment 31. The type-bars are each provided at their inner ends with a plurality of type 32, varying according to whether the machine has a single case shift or a double case shift. In the present instance the machine is constructed with a double case shift, and each type-bar is therefore provided with three types; one representing the upper case, another the lower case, and the third figures or other characters. If one of the keys 24 is depressed the lever 23 thereof will operate

the horizontally arranged levers 20 and 21, and through the links 26 and 27 will move the type-bar 29 on its pivot rod 30 to force the type upwardly and rearwardly to make an impression on the work sheet about the platen 14.

The frame part 12 on which the platen carriage 13 is mounted is held to have a vertical movement relative to the frame part 11 to adapt the platen carriage to be placed in a normal operative position or in a compact and inoperative position. The frame part 12 has side plates 33 which are connected together at the rear portion thereof by a carriage bed 34 along which the carriage 13 is adapted to travel. At the forward edge the side plates 12 have an outwardly turned portion 35, which is adapted to move vertically in a similarly formed groove 36, located in an offset portion 37 of each of the side plates 15 of the base or frame part 11. Each offset portion 37 is provided with a vertical slot 38 arranged parallel to the grooves 36 and extending through each slot 38 is a screw or bolt 39. The screws or bolts 39 each have threaded inner ends to engage a threaded aperture in the side plates 33 of the frame part 12 and each screw or bolt is provided with a guide collar 40 and a knurled or other head 41 at its outer end. The collar 40 is adapted to move and be guided in an enlarged portion 42 of the vertical slot 38 at each side of the machine. If the screws on the opposite sides of the machine are released by means of the heads 41, the frame part 12 may be raised or lowered according to whether the machine is to be placed in an operative position or in a compact position, and by tightening the screws these parts may be held in such compact or operative positions. By this means a simple and effective frame construction is provided whereby the platen carriage may be mounted upon one frame part and the type action on another frame part, and the machine collapsed without disconnecting any parts of the operating mechanism.

In Figs. 1 to 7 the type segment is adapted to be raised or lowered with the type-bars 29 for case shift purposes and said segment 31 is mounted upon a shift frame 43. This frame has forwardly extending bars 44 to which the type basket 45 is held, the latter forming a rest for the forward ends of the type-bars. Two pairs of arms 46 and 47 are located on opposite sides of the machine. The arms 46 are pivoted at their inner ends to the shift frame 43, and at their outer ends are pivoted to the sides or plates 15 of the base 11, while the lower arms 47 are pivotally held at their inner ends to the shift frame, and at their forward ends are held to a transversely extending rod 48. One of the arms 47 forms a part of a bell-crank 49.

At the upper end of the arm 49 of said bell-crank is a roll 50, and said roll 50 enters slots 51 and 52 of shift levers 53 and 54 respectively. The shift levers 53 and 54 each have a key 55 forming a part of the keyboard, said levers being pivoted at their inner ends to an inwardly extending lug 56. The slots 51 and 52 of the levers extend in opposite directions and intersect and in their normal position serve to lock the type segment in its normal position. If one of the shift levers is depressed, as the lever 53 for example, this will cause the slot 51 to force the roll 50 rearwardly, and this will cause the bell-crank 48 to lower the type segment relative to the platen 14. If the shift lever 54 is depressed the slot 52 thereof will force the roll forwardly, and this will elevate the type segment, thus giving two shift positions of the type segment one above and the other below the normal position thereof. A spring 57 is adapted to restore and hold each shift lever in its normal position, and one or more springs 58 at each side of the machine may be employed to hold the type segment and frame in their normal position and as a means to counterbalance the weight thereof.

On the frame part 12 are mounted the associated parts for the platen carriage. These parts are substantially the same, except as to their mounting and relation to other parts, as in the Corona typewriter, and neither these parts nor the type action or case shift are claimed specifically herein, but only broadly in their different relations and mountings. The platen carriage is provided with a base 59 having anti-friction rolls 60 along one end thereof, and at the forward edge of said base is a track 61 having anti-friction or other devices which serve to guide the carriage in its transverse travel along the bed 34 under the tension of a spring drum or other motor, as is usual in typewriting machines. The carriage may be provided with a paper apron 62 and mounted in the paper apron may be one or more pressure rolls 63 and at the forward edge thereof a suitable scale 64. The platen may be provided with a knob 65 at one end and line spacing mechanism 66 at its other end, whereby the said platen may be rotated in the usual way. Paper fingers 67 may be held to be adjusted lengthwise of the platen, and there may be provided means, as guides 67^a for alining the type at the printing point.

Suitable ribbon mechanism is mounted upon the frame part 12. This mechanism may include means for feeding the ribbon lengthwise, means for vibrating the ribbon, and also means for reversing the direction of feed of the ribbon, though in the drawings only the mechanism for feeding the ribbon lengthwise is shown. The ribbon spools

68 are rotatably held upon shafts 69, and at the upper ends of each shaft is a nut 70 by which each spool may be held to rotate with the shaft or to rotate independently thereof, as desired. Each shaft 69 is provided with a worm wheel 71 and engaging each worm wheel is a worm 72. The worm 72 is held to a shaft and on the outer end of each worm shaft is a toothed or ratchet wheel 73 which is adapted to be engaged by a pawl 74. The pawl 74 is mounted upon a reciprocatory universal bar 75, and as the bar 75 reciprocates, as will be presently described, a step-by-step rotary movement will be imparted to the worms and said worms will rotate the worm wheels and their shafts 69, and whichever spool is held or locked by its nut to one of the shafts, thus the ribbon may be fed from one side of the machine to the other in either direction, according to which nut 70 is tightened and the other loose.

The universal bar 75 is mounted to reciprocate back and forth on the main frame part 12, and has a downwardly extending flange 76 at the forward edge thereof, which is adapted to be engaged by a part 77 of each type-bar during the printing movement thereof. The universal bar has angular ends 75^a, Figs. 1 and 7, on which are lugs, and these lugs are pivotally held to parallel arranged arms 78 at each side of the machine, said arms 78 being pivotally held to the sides 33 of said frame part 12. The universal bar may be forced in one direction by a spring if desired, against the action of the type-bars and the ends thereof may be provided with a tappet 79 which is adapted to engage the upturned end 80 of a dog carrier 81. The dog carrier 81 may be provided with the usual limber and fixed dogs 105 and is adapted to engage a rack on the carriage to control the letter space movement thereof, as in the Corona typewriter, though the construction of the escapement mechanism may be varied as desired. The universal bar is thus movable with the frame part 12 from its normal position to a compact and inoperative one, or vice versa, and is adapted not only to operate the escapement mechanism, but also the ribbon mechanism, including the ribbon vibrator.

The universal bar may be operated to trip the escapement without operating the type-bars or printing instrumentalities. A space bar 82 is suitably mounted on the transversely extending bar 18 and may be connected by a link 83, lever 84, and rod or link 85 to a space lever 85^a, shown in dotted lines in Figs. 2 and 3. The space lever is pivotally held to lie normally alongside of one of the type-bars, and may be substantially the same in construction as one of the type-bars except that it is shorter and free of type, and so arranged that when the space bar 82 is depressed the space lever may

4

be forced upwardly and rearwardly to move the universal bar and thereby trip the escapement, there being a spring 85^b for restoring the space bar to its normal position.

5 Figs. 3 to 10 show a collapsible machine of somewhat the same character shown in the other figures, except that the parts are changed to adapt the platen carriage for case shift instead of the type segment shift, 10 as in the said other figures. As shown there is a base or main frame part 86, and vertically movable with respect to the frame part 86 is another main frame part 87. The main frame part 87 itself comprises relatively 15 movable parts 88 and 89. The part 88 has side plates or members 90 which are connected together by the transversely extending carriage bed 91 along which the carriage 92 is adapted to travel, said carriage being 20 provided with a platen 93 of the usual or of any preferred construction. The side plates 90 at the forward portion thereof are each provided with an inturned part 94, and said inturned part is adapted to be vertically adjustable in a groove 95 in the part 89. The 25 part 89 at each side of the machine is provided with a vertical slot 96 through each of which extends a shank or stem 97 of a bolt 98. Each bolt or screw 98 has its inner 30 end threaded to engage a threaded aperture in one of the side plates 90, and each screw or bolt is provided with a milled head 99 by which the screw may be released or tightened. By releasing the screws the parts 35 88 may be relatively adjusted with respect to the parts 89, and the parts as thus adjusted may be held by means of the screws 98. This permits the carriage and the part 88 on which the carriage is mounted to 40 45 gether with such other mechanism as may be mounted upon the part 88, to be moved from a normal operative position to a compact and inoperative one with respect to the part or parts 89 and the base 86.

45 The parts 88 and 89 while relatively movable are together movable for case shift purposes on the base member 86. At the forward vertical edge of each part or member 89 is a dove-tail groove 100 which is 50 engaged by a tongue or portion 101 at the rear vertical edge of each of the side plates 102 of the frame part 86. The tongue and groove connection 100 and 101 properly hold the frame parts together and permit 55 the frame part 87 to be elevated or lowered for shift purposes. To shift the platen to adapt the type-bars to have a plurality of characters thereon, a shift mechanism 102 somewhat similar to that already described 60 is employed. The shift mechanism has two shift levers 103 and 104 and both shift levers are pivoted at their inner ends to an extension 105 on one of the side plates 102 of the frame base. These levers each have a key 65 106 at their outer ends and intermediate 70 their ends have upwardly extending portions 107 and 108 respectively. The parts 107 and 108 are hook-shaped to provide curved slots or portions 109 in the part 107 and 110 in the part 108. The slotted portions extend 75 in opposite directions, one forwardly and the other rearwardly, and entering said slotted portions is a roll 111. The roll 111 is carried upon an arm 112 of a bell-crank lever 113 and this lever is secured to a shaft 114. There may be an arm 113 at the opposite side of the machine to balance the shift frame and the rear end of the arm 113 or each arm thereof, if more than one, may be slotted to engage the stud of a pin or bolt 80 115. If the lever 103 is depressed the roll 111 will be forced rearwardly and this will lower the frame part 87 to which the arms 113 are connected, while if the lever 104 is depressed, as shown in Fig. 8, the frame 85 part 87 with the platen carriage will be elevated. The shift levers may be restored to their normal position by means of springs 116 or otherwise, and there may be one or more springs, not shown, for counterbalancing the weight of the frame part 87 and the parts mounted thereon. The normal position of the platen carriage is for the center type or character on the type-bar and in one shift movement the platen carriage is lowered from the normal position and in the other case shift movement it is raised from the normal position. Except as described, the construction of the parts, including the type 90 action, ribbon mechanism, and escapement 95 mechanism, as well as the mounting of the universal bar and the action thereof is substantially the same as shown in the other figures.

95 It will be evident from the foregoing 105 that a simple and efficient collapsible typewriting machine is provided in which either a platen shift or type segment shift may be employed; that the main frame is so constructed that the vertical collapsing or 110 extension movement of the frame part is in a vertical direction without extending the movable frame part to the forward portion of the base member; and that while a construction is shown wherein the frame part 115 with the carriage mounted thereon has a vertical direct movement only, it will be understood that where the platen is shifted the construction may be such as to move in a different direction from that of simply a 120 vertical plane.

Having thus described my invention, I claim as new and desire to secure by Letters Patent:—

1. In a typewriting machine the combination of a main frame having one part vertically slidable relatively to another part, a platen carriage, escapement mechanism, ribbon mechanism, all mounted upon said vertically slidable frame part, a keyboard 125 130

mounted upon the other part of the frame, and means for imparting a case shift movement to the platen carriage.

2. In a typewriting machine the combination of a transversely divided main frame comprising a stationary forward part and a relatively movable rear part held to said forward part to slide vertically at the rear thereof, a platen carriage supported on said vertically slideable part, a key action and type segment mounted on said stationary part, ribbon spools mounted on said vertically slideable part above and on opposite sides of the type segment, and a universal bar mounted on said vertically slideable part above and at the rear of the type segment, said platen carriage and universal bar being movable downwardly at the rear of the type segment and said ribbon spools being movable downwardly at opposite sides of the type segment when the vertically slideable frame part is moved downwardly to compact the machine.

3. In a typewriting machine the combination of a base frame part, a keyboard and type action thereon, a second frame part comprising members movable relatively to each other and to said base frame part, a platen carriage supported on one of said members, connections between said members of the second frame part whereby the platen carriage will be maintained in an upright position when its supporting member is shifted to move the platen carriage from its normal operative position to a more compact inoperative position, and means for moving the members of said second frame part in unison relatively to the base frame part for imparting a case shift movement to the platen carriage.

4. In a typewriting machine the combination of a main frame divided vertically transversely of the machine, a keyboard and type action mounted on the forward part of the frame, a platen carriage supported on the rear part of the frame and movable therewith vertically from a normal elevated operative position downwardly to a point at the rear of the type action, coöperating relatively slideable means carried by said frame parts for maintaining the platen carriage in an upright position at all times, and means for locking the rear part of said frame in its elevated position.

5. In a typewriting machine the combination of a main frame divided vertically transversely of the machine, a keyboard and type action mounted on the forward part of the frame, a platen carriage, ribbon mechanism, escapement mechanism, and a universal bar, operable by the type bars all supported on the rear part of the frame and movable therewith from a normal elevated operative position downwardly to a lower inoperative position relatively to the type bars

and coöperating relatively slideable means carried by said frame parts for maintaining the platen carriage and its associated parts in an upright position at all times.

6. In a typewriting machine the combination of a main frame divided transversely of the machine, a keyboard and type action mounted on the forward part of the frame, a platen carriage supported on the rear part of the frame and movable therewith from a normal elevated operative position downwardly to a point at the rear of the type action, coöperating slideably interlocked means carried by said frame parts for maintaining the platen carriage in an upright position at all times, and key-operated means supported on the forward part of said frame for imparting a case shift movement to the platen carriage.

7. In a typewriting machine the combination of a main frame having vertically arranged relatively slideable parts, a platen carriage, escapement mechanism, ribbon instrumentalities, all mounted upon one part of said frame and movable downwardly therewith while upright to reduce the height of the machine, a keyboard mounted on another part of said main frame, a type bar for each key adapted to be located forward of the carriage when the parts are moved to a compact position, and means for imparting a case shift movement to the platen.

8. In a typewriting machine the combination of a main frame having two parts slideably held together and movable relatively to each other to reduce the cubical dimensions of the machine, one of said parts being normally stationary and the other comprising members movable relatively with respect to each other and to the stationary frame, a keyboard and type bars mounted upon the stationary part of the frame, a platen carriage and ribbon instrumentalities mounted upon one member of the movable frame part and movable with said member from a normal operative position to a more compact inoperative position, and means for shifting both members of the movable frame part for imparting a case shift movement to the platen carriage.

9. In a typewriting machine the combination of a base frame part, a keyboard and type bars mounted upon said base frame part, a main frame part comprising relatively slideable members to adapt said frame part to be extended vertically in a normal operative position and to be collapsed downwardly to reduce the height of the machine, a platen carriage mounted upon one member of said main frame part, means for slidably holding the other member of the main frame part to the base frame part, and means for bodily moving said main frame part relatively to the base frame part for imparting a case shift movement to the platen carriage.

- 6
10. In a typewriting machine the combination of a stationary frame part, a vertically slideable frame part held to said stationary part to move vertically downwardly at the rear thereof while upright from a normal operative position to an inoperative position to reduce the height of the machine, a platen carriage mounted on said slideable frame part, a keyboard and type action mounted on said stationary frame part, and case shift means supported on said stationary frame part for imparting a vertical case shift movement to the platen carriage and its supporting frame part.
15. 11. In a typewriting machine the combination of a three-part main frame comprising a forward part, a keyboard and type action mounted on said forward frame part, an intermediate vertically movable frame part, a shift key and connections mounted on said forward frame part for imparting a vertical case shift movement to said intermediate frame part, a rear frame part held to said intermediate frame part, a platen carriage mounted on said rear frame part, said rear frame part being movable vertically at the rear of the type action from a normal elevated operative position to a lower inoperative position to reduce the height of the machine, and means for maintaining the platen carriage in an upright position during the compacting movement thereof.
20. 12. In a typewriting machine, a main frame part, a key action and type bars mounted on said main frame part, a second relatively movable main frame part, a platen carriage mounted on said second frame part and having a vertical case shift movement and an abnormal vertical compacting movement at the rear of the type bars, and means for maintaining the platen carriage in an upright position at all times.
25. 13. In a typewriting machine the combination of a main frame divided vertically transversely of the machine, a keyboard and type action mounted on the forward part of the frame, a platen carriage supported on the rear part of the frame and movable therewith vertically from a normal elevated operative position downwardly to a point at the rear of the type action, means for maintaining the platen carriage in an upright position during the movement thereof toward and from its normal position, and means for locking the rear frame part in its elevated and lowered positions.
30. 14. In a typewriting machine the combination of a divided main frame comprising a forward part and a relatively movable rear part, a keyboard mounted on said forward frame part, a platen carriage supported on said rear frame part and movable therewith from a normal elevated operative position downwardly to a more compact operative position, sliding connections between said frame parts for maintaining the platen carriage in an upright position during the movement thereof toward and from its compact position, and means for imparting a case shift movement to the platen carriage.

This specification signed this twenty-ninth day of April A. D. 1916.

BENJAMIN W. TUCKER.
